UNITED STATES PATENT OFFICE.

WINCENTY HOFMAN, OF SOUTH CHICAGO, ILLINOIS.

FLYING MACHINE.

Application filed February 6, 1925. Serial No. 7,328.

To all whom it may concern:

Be it known that I, WINCENTY HOFMAN, a citizen of Poland, residing at South Chicago, in the county of Cook and State of Illinois, have invented certain new and useful Improvements in Flying Machines, of which the following is a specification.

This invention relates to flying machines of the type propelled by wings and the chief 10 object of the invention is the provision of economical means for propelling the wings.

A further object of the invention is the provision of a turbine driven by a fluid such as compressed air for propelling the wings.

15 Another object of the invention is to utilize the pressure of the air during the horizontal flight of the machine for the auxiliary motive power of the turbine.

A still further object of the invention is 20 the provision of improved steering means of the flying machine.

With the above general objects in view and others that will appear as the nature of the invention is better understood, the same 25 consists in the novel construction, combination and arrangement of parts hereinafter more fully described, illustrated in the accompanying drawings and pointed out in the appended claims.

30 In the drawings forming a part of this application, and in which like designating characters refer to corresponding parts throughout the several views,

Figure 1 is a side elevational view of the 35 device with a sectional view of the housing inclosing a part of the device;

Figure 2 is a top plan view of the rear portion of the device broken on an irregular transversal line from the main body of the 40 device, the figure being taken substantially on line 2-2 of Figure 1;

Figure 3 is a transversal sectional view of a portion of the platform and of the wing taken on line 3-3 of Figure 1;

45 Figure 4 is a longitudinal sectional view of a portion of the machine taken on horizontal plane indicated by line 4-4 of Figure 1 and looking in the direction of the arrows; and

50 Figure 5 is a transversal sectional view of the turbine taken on line 5-5 of Figure 1.

Referring to the drawings, there is shown a platform 10 with a landing device affixed therebelow and consisting of landing device 55 11 at the front end of said platform and of a support 12 at the rear end thereof.

Longitudinally of the platform disposed thereabove is the main shaft 13 supported on the platform by means of upright beam 14 which at its upper end is provided with 60 a bearing 15 within which the shaft rotates. Forwardly of said bearing 15 and adjacent thereto a thrust bearing 16 is rigidly mounted upon said shaft preventing the rearward shifting of the shaft. 65

Rearwardly of said support 14 a cone-shaped drum 17 is positioned on the shaft and rigidly secured thereto by means of spider 18. The forward wider end of the drum is open for receiving the air during 70 flight of the machine. Vane or blade 19 is spirally arranged within the cone-shaped drum. The rear narrower end of the drum is flared as at 20 as plainly seen on Figure 4.

Bowl 21 is positioned rearwardly of drum 17. The flared end 20 of the drum is positioned within the mouth of the bowl so that the forward end of the bowl overlaps said flared end 20 as seen on Figure 4. The bowl being stationary the drum rotates with the 80 shaft therewithin, and owing to the connection between the bowl and the drum as hereinabove described no air will escape from the bowl. As already mentioned the bowl remains in a stationary position and is rigidly secured to support 22 mounted on platform 10 as seen on Fig. 1. 85

The rear end of the bowl is covered by plate 23 which is riveted to the bowl as seen on Figs. 1 and 3, said plate 23 being provided with a central aperture accommodating shaft 13 and within which the shaft freely rotates. To strengthen the structure bearing 24 is rigidly secured by the front end to plate 23, said bearing being also provided 95 with a bore which is in alignment with the aperture in plate 23. The other end of bearing 24 is affixed to the turbine which will be hereinafter described.

Plate 23 is provided with port and nozzle 100 25 upon which tube 26 is positioned. The other end of tube 26 is affixed to nozzle 27 through which the air passes to the turbine.

It is not my intention to limit myself to the particular turbine shown in the drawings of the present application. There are other known types of turbines which may be employed and which are capable of utilizing an auxiliary driving power in addition to the primary power. 105

For the purpose of illustration merely I have shown a turbine comprising an outer

cylindrical casing 28 with a front cover 29 and rear cover 30, said casing being stationary and being supported on the platform by means of support 31. An inner revolving barrel 32 is positioned within said casing and rigidly secured to the shaft 13 by means of spiders 33. A series of longitudinal blades 34 is provided upon the barrel and rigidly mounted thereon. Said blades remain interposed between the barrel and the casing as seen on Fig. 5.

Transversely of the barrel and of said blades a series of partition walls 35 is positioned which walls are also rigidly secured to the barrel. Said blades and partition walls will form a plurality of pockets of substantially square formation as is obvious. On the drawings there are shown four rows of pockets transversely disposed in respect 20 of the barrel as is seen on Fig. 4.

Above the nozzle 27 another nozzle 36 is provided through which the compressed air is supplied to the turbine from the air compressing machine. Both nozzles are set 25 at an incline in the direction of the rotation of the barrel so that the compressed air passing through each nozzle may strike directly and substantially at right angle each blade 34 as it passes the inner opening of the nozzle. Thus a thrust upon each passing blade 30 will be imparted by the compressed air and consequently a rotary movement of the barrel will be effected.

The above mentioned air compressing machine comprises an engine 37 and air compressor 38 which is connected with the engine by means of driving belt 39. The air compressing machine is further provided with air tank 40. It should be mentioned 40 that the air compressing machine may be of any known type and the type shown on the drawings is for the purpose of illustration only.

The compressed air passes to the turbine through pipe 41 and hose 42. Said pipe 41 is provided with a valve and crank 43 which connects to arm 44, the other end of the arm being pivoted to lever 45 by means of which the valve in pipe 41 is operated as is 45 obvious.

The cylindrical casing 28 at its lower portion and adjacent the first transversal series of pockets formed by blades 34 and partition walls 35 is provided with vent 46 permitting the exhaust of the compressed air in the said pockets as the revolving barrel rotates. The air exhausted therefrom passes through the U-shaped tube 47 into the next transversal series of pockets. The other end 60 of said tube is disposed at an incline, as seen on Fig. 5, so that the air may squarely hit blades 34 in said next series of pockets.

The air exhausts from the second series of pockets through vent 48 and tube 49 and 65 is led to the third transversal series of

pockets. The other end of said tube 49 is disposed at an incline and leads to the third series of pockets. The air exhausts therefrom through vent 50 and tube 51 and is led into the fourth series of the pockets until exhausted to the atmosphere through vent 52. Thus it will be seen that the force of the compressed air driven into the turbine through hose 26 or hose 42 is successively utilized to drive the revolving barrel of the 75 turbine before it is exhausted into the atmosphere.

As my invention is intended for an upright ascent of the flying machine I have not shown any means for horizontal flight. 80 For this purpose one or more propellers driven by any known means may be provided.

The rear end of shaft 13 is provided with a bevel gear 53 meshing with a bevel gear 85 54 keyed to the transversal crank shaft 55. Arms 56 connect the crank shaft with the wings which are disposed laterally of the platform and hinged thereto as at 57. Said wings are comprised of inner planes 58 to 90 which arms 56 are connected, and of outer sections 59 which are hinged to said inner planes by hinges 60 as illustrated on Fig. 3. The inner edges of planes 58 are tapered as at 61 so that the wings may have un- 95 impeded upward movement.

Fig. 3 shows the position of one of the wings when making a downward stroke with the outer section open. On upward movement of each wing the outer section will 100 drop on its hinges as is apparent. It is therefore clear that the air during the downward movement of the wings will afford greater resistance than during the upward movement of said wings. Thus it will be 105 possible for the machine to ascend.

The operation of the machine is as follows: the compressed air from the air tank 40 is let into the turbine on opening of valve 43. The turbine rotates the main shaft 13 110 110 which in turn operates crank shaft 55, the latter shaft being supported on the platform by braces 62. Said crank shaft reciprocates wings 58 through arms 56 causing the upward movement of the machine. 115

Drum 17 on the main shaft rotates simultaneously with the revolving barrel of the turbine. On horizontal forward flight of the machine the air collects and concentrates in said drum reaching a degree of compression in bowl 21 wherefrom it is passed into the turbine through hose 26. During a rapid horizontal flight of the machine the pressure of the air increased by its resistance will be very great and the degree of 120 its compression in the bowl will be corresponding. Blade 19 in the drum is not absolutely necessary, although it forces the air into the bowl and tends to increase the degree of compression. 125 130

Whenever expedient the supply of the compressed air from the air compressing machine may be shut off by closing valve 43. Then the air in the bowl alone will be sufficient to operate the turbine and the wings at least to the extent of levitation or gradual descent of the machine.

Housing 63, shown in section in Fig. 1, provides shelter for the hereinabove described mechanism.

For the lateral steering of the machine rudder 64 is provided at the rear end of the platform and is pivoted in the rudder-post 65 by means of pin 66. The lower end of said pin is bent to form crank 67. Pin 66 being rigidly secured to the rudder-stock 68 by means of pin or screw 69 enables the rudder to turn with the pin. Arm 70 is pivotally connected at its rear end to said crank 67 and at its forward end to crank 71 formed at the lower end of steering post 72. Steering wheel 73 is provided at the upper end of said steering post. Steering column 74 is rigidly secured to the platform and the steering post turns therewithin. Rearwardly of said steering post a chair 75 for the operator is positioned upon the platform.

For the upward and downward steering of the machine a pair of horizontal planes 76 is provided rearwardly of the platform, each plane being positioned laterally of the rudder. Each of the said planes is of substantially trapezoid formation and by its longer parallel side is attached to the platform by means of hinges 77. The forward leaves of said hinges are rabbeted in the platform and the rear leaves thereof are rabbeted in the planes as plainly seen on Fig. 1.

A single rod 78 provides a pivotal connection for the two series of the leaves of said hinges, the leaves rabbeted in the planes being rigidly secured to the said rod by pins 79 as seen on Fig. 2. Owing to this arrangement the movement imparted to only one plane will be transmitted by said rod to the other plane. Said rod by its central portion passes through an aperture made in the rudder-post 65 and in such manner does not interfere with the operation of the rudder.

Plate 80 with projecting lug 81 is rigidly mounted upon the upper surface of one of the said planes. Arm 82 at its rear end is pivoted to said lug and by its forward end is pivoted to lever 83. Said lever at its lower end is pivoted to the platform as at 84 and has an arcuate rack bar 85 disposed laterally thereof where the ratchet bar 86 engages.

From the description made it will be apparent that on turning one plane by lever 83 the other plane will turn also since both planes are rigidly connected by means of rod 78.

While there is described herein a preferred embodiment of the present invention,

it is nevertheless to be understood that minor changes may be made therein without departing from the spirit and scope of the invention as claimed.

What I claim as new is:

1. In a flying machine having a platform, a main shaft disposed thereabove, an air turbine rotating said shaft, a drum upon said platform for compressing the air on forward horizontal flight of the machine, 70 hose connection between said drum and said turbine, a crank shaft in operative engagement with said main shaft, wings pivotally mounted upon said platform, and connecting arms between said crank shaft and said wings.

2. In a flying machine having a platform, a main shaft disposed thereabove, an air turbine rotating said shaft, a drum upon said platform for collecting the air on forward horizontal flight of the machine, a bowl in association with said drum wherein the collected air is compressed, hose connection between said bowl and said turbine, a crank shaft in operative engagement with 85 said main shaft, wings pivotally mounted upon said platform, and connecting arms between said crank shaft and said wings.

3. In a flying machine having a platform, a main shaft disposed thereabove, an air 95 turbine rotating said shaft, a primary means for operating said turbine, a secondary means for operating the same, a crank shaft in operative engagement with said main shaft, wings upon said platform, and connecting arms between said crank shaft and said wings.

4. In a flying machine having a platform, a main shaft disposed thereabove, an air turbine rotating said shaft, a primary 105 means for operating said turbine, a drum on said platform, said drum constituting a secondary means for operating said turbine, a crank shaft in operative engagement with said main shaft, wings upon said platform, 110 and connecting arms between said crank shaft and said wings.

5. In a flying machine having a platform, a main shaft disposed thereabove, an air turbine rotating said shaft, means supplying the motive power to said turbine, a crank shaft in operative engagement with said main shaft, wings upon said platform, and connecting arms between said crank shaft and said wings.

6. In a flying machine having a platform, a main shaft disposed thereabove, an air turbine rotating said shaft, fluid compressor supplying the motive power to said turbine, a crank shaft in operative engagement with 125 said main shaft, wings upon said platform, and connecting arms between said crank shaft and said wings.

In testimony whereof I affix my signature.
WINCENTY HOFMAN.
